UNITED STATES PATENT OFFICE.

JAMES S. OLIVER, ADOLPHUS D. OLIVER, AND NOBLE B. OLIVER, OF SAN ANGELO, TEXAS.

WELL-DRILLING MACHINE.

Application filed May 16, 1923. Serial No. 639,328.

To all whom it may concern:

Be it known that we, JAMES S. OLIVER, ADOLPHUS D. OLIVER, and NOBLE B. OLIVER, citizens of the United States, residing at 5 San Angelo, in the county of Tom Green and State of Texas, have invented certain new and useful Improvements in Well-Drilling Machines, of which the following is a specification.

10 This invention relates to well drilling machines, and has for one of its objects to improve the construction and increase the efficiency and utility of devices of this character.

15 Another object of the invention is to provide a device of this character capable of being transported from place to place and foldable into relatively small space for transportation or storage.

20 With these and other objects in view, the invention consists in certain novel features of construction as hereinafter shown and described and then specifically pointed out in the claim, and in the drawings illustrative 25 of the preferred embodiment of the invention.

Figure 1 is a side elevation from one side, and

30 Fig. 2 is a side elevation from the opposite side.

Fig. 3 is a plan view, with the supporting frame in section on the line 3—3 of Fig. 1.

Fig. 4 is an enlarged detail in section on the line 4—4 of Fig. 1.

35 Fig. 5 is an enlarged sectional detail of the tension device.

Fig. 6 is an enlarged detail, partly in section, of the gear shifting mechanism.

40 Figure 7 is an enlarged side view partly in section of the adjustable bearings of the winding drum shaft and the shipper shaft.

45 The improved apparatus includes an oblong base frame of spaced side rails 10—11, transverse end members 12 and 13, an intermediate transverse member 14, vertical rear corner members or posts 15, forward corner posts 16, upper rear transverse frame members 17 and obliquely directed braces 18 and 19.

50 The forward posts 16 are inclined outwardly, slightly, as shown in Figs. 1 and 2, and are likewise extended above the line of the braces 18.

The rear posts 15 are likewise extended upwardly and are provided with bearings 20 which support a transverse shaft 21 on which a cable guide pulley 21' is mounted.

55 A short longitudinal frame member 22 is supported on the frame members 12 and 14, and carries a bearing 23 coaxing with a 60 similar bearing 24 on the rail 10, to support a shaft 25, the shaft carrying the main band wheel 26, and provided with a crank 27.

An operating beam 28 is pivoted at one end to a shaft 29 supported in bearings, one 65 of which is shown at 30 on the posts 15. The beam is provided with a cable guide pulley 31 intermediate the ends, as shown.

70 Attached to the forward posts 16 are transverse supports 32 and 33, and connected to these supports are spaced vertical guides 34 between which the free end of the beam 28 operates and by which it is prevented from lateral displacement.

75 The "mast" portion of the improved apparatus constitutes an extension of the forward posts 16 and is represented as a whole at 35 and hingedly united at 36 to the posts, so that the mast can be folded down as indicated by dotted lines in Fig. 1. Braces 37 80 are detachably connected as at 38 and 39 to the posts 15 and mast 35, and hold the mast in vertical and operative position, but will be releasable to permit the mast to be folded, as will be obvious. At its upper end, 85 the mast is provided with a cross head 40 carrying cable guide pulleys 41 and 42 for the sand pump line 43, and with a cable guide pulley 44 for the main drill line 45.

85 Mounted for rotation by bearings 46 on 90 the frame members 10 and 11 is a main drive shaft 47 carrying a drive pulley 48 operative by a drive belt 49 from any suitable source of power, not shown.

95 Mounted loosely on the shaft 47 is a belt pulley 50 in alinement with the band pulley 26 and with an endless drive belt 51 operating over the pulleys.

100 The pulley 50 is formed with an internal friction clutch face with which a cone clutch member 52 slidably on the shaft 47 is adapted to be engaged.

105 Slidable on and rotative with the shaft 47, for instance by a feather or key 53, is a sleeve 54, the latter coupled to the clutch member 50 by arm 55,

Slidably supported by guide members 56 and 57 on the frame members 10 and 11 is a shipper rod 58, and connected to the shipper rod is a yoke device 59, the latter engaging 5 in an annular groove in the sleeve 54. By this arrangement when the shipper rod is moved longitudinally in one direction, the clutch member 50 will be forced into contact with the member 52 and transmit the motion 10 of the shaft 47 to the belt wheel 26, and when the shipper rod is moved in the opposite direction, the clutch members will be separated and the motion of the belt pulley stopped.

15 At one end the rod 58 is forked as shown at 60 and provided with transverse pins 61 through the forks. Mounted for rotation in hangers 62 on the frame members 11 is a rod 63 having the ends upturned as at 64 and 20 65, the portion 64 extending upwardly between the pins 61 and preferably curved as shown in Fig. 6 to reduce the friction, while the pins 61 are also preferably provided with antifriction rollers as shown in Fig. 6, 25 for the same purpose. The upturned portion 65 constitutes a hand lever by which the rod 63 may be rotated. The lever member 65 is arranged to be held in adjusted position in any suitable means, such as by 30 a toothed segment and pawl device indicated at 66 and 67. By this arrangement, the clutch member 52 is operative from the vicinity of the mast 35, as will be obvious.

Attached to the frame member 10 is a 35 swivel bearing 67, and slidably mounted on the frame member 11 is a bearing 68, the bearings supporting a shaft 69 on which the sand line winding drum 70 is mounted for rotation with the shaft.

40 Attached to the frame member 10 is a bearing 71, and mounted on the member 11 is a like bearing 72, the latter bearings supporting a shaft 73 which carries a cable winding drum 74 for main drill cable 45.

45 Attached to the frame member 10 is a swivel bearing 75, and slidably mounted on the frame member 11 is a bearing 76, the latter bearings supporting a shaft 77.

The shafts 73 and 77 are provided 50 respectively with engaging gear 78 and pinion 79, to provide for the rotation of the shaft 73 from the shaft 77.

55 The shaft 47 is extended beyond the frame member 11 and is provided with a friction drum 80, while the shafts 69 and 73 are provided respectively with friction drums 81 and 82.

60 Connected respectively to the shafts 69 and 77 are pull-rods 83 and 84, and mounted on one of the vertical members 16 are plates 85 and 86 on which levers 87 and 88 are 65 swingingly supported at 89 and 90.

66 The levers are provided respectively with cam devices coupled to the rods 83 and 84, to enable the rods to be independently moved

longitudinally to draw the drum 81 or 82 into engagement with the central drum 80, and transmit the motion of the shaft 47 to either of the shafts 69 or 73, from a position 70 near the mast.

Thus by manipulating the three levers 65-87 and 88, the motion of the shaft 47 may be transmitted to the main band wheel 26 and thence to the beam 28, or to either the winding drum 70 or 74 the object to be 75 hereinafter explained.

Attached to the post members 15 and to the braces 19 are brackets 91, and attached to the upper horizontal sides of the brackets are gear racks 92.

Attached across the post members 15 is a support 93, and slidable through the support near the ends are pull rods 94, each rod being provided with a pull spring 95 and stop plate 96 and operating to hold the rods 85 yieldably in outer position. At its inner end, each rod is connected to a bearing 97, and mounted for rotation through the bearings is a shaft 98, and mounted on the shaft 90 and rotative therewith are gear pinions 99 in constant engagement with racks 92.

Mounted on the shaft 98 is a cable guide pulley 100.

The crank 27 is coupled to the beam 28 by a connecting bar 101.

The main drill line 45 is attached at one end to the main winding drum 74 and is passed thence over the guide pulley 100, thence beneath the guide pulley 31, thence over the guide pulley 44 and down to the 100 drill element, not shown.

Motion is imparted to the shaft 47 by the drive belt 49, and the rod 63 actuated by the hand lever 65 to close the clutch device 52 and transmit motion to the main band wheel 26 and thence to the crank 27, connecting bar 101, and beam 28, and cause the pulley 31 to actuate the drill cable. As the beam 28 is operated and strain applied to the drill cable, corresponding strain is applied to the shaft 98, and the latter moved against the resistance of the springs 95, to thus take up the slack of the drill cable and keep it in taut condition.

As the drilling proceeds, the drum 74 is 115 slackened up to permit the drill cable to be drawn out as fast as required. As the cable is wound upon the drum 74, it constantly moves toward one end of the drum, consequently the guide pulley 100, which slides 120 freely on the shaft 98 will be correspondingly moved longitudinally of the shaft and this lateral movement of the pulley changes the pull or leverage on the shaft 98, but by coupling the ends of the shaft to the racks 92 by the pinions 99 the shaft is maintained 125 constantly at right angles to the frame members 10 and 11, no matter where the pulley 100 is located on the shaft 98.

If the cable is to be wound upon the drum 130

74, the lever 88 is moved rearwardly to force the friction drum 81 into engagement with the central power drum 80.

If the sand line is to be wound upon the drum 70, the lever 87 is actuated to apply a pulling force to the rod 84 and thus move the drum 81 into engagement with the central drum 80.

Thus the various motions are all accomplished by simply manipulating the three small levers 65, 87, and 88, as before described, the levers being independently operative.

The apparatus will preferably be mounted on carrier wheels indicated at 102.

A suitable brake device is arranged to check the friction pulley 82, while a similar brake device 103 which is attached to the adjacent sill member 11 of the supporting frame checks the pulley 81.

The preferred embodiment of the invention is disclosed in the drawings and set forth in the specification, but it will be understood that modifications within the scope

of the claim may be made in the construction without departing from the principle of the invention or sacrificing any of its advantages.

What is claimed is:—

In an apparatus of the class described, a supporting frame, a mast extending from said frame and carrying a cable guide pulley, a beam swinging from said frame and carrying a cable guide pulley, spaced rack bars supported on said frame, a shaft carrying gear pinions engaging said rack bars, a cable guide pulley carried by said shaft, bearings engaging said shaft, pull rods extending from said bearings, springs engaging said rods and operating to hold said shaft yieldably in position, and a cable attached at one end relative to said frame and leading over said several cable guide pulleys.

In testimony whereof, we affix our signatures hereto.

JAMES S. OLIVER.
ADOLPHUS D. OLIVER.
NOBLE B. OLIVER.
